UNITED STATES PATENT OFFICE.

JESSE M. PEASE, OF BUFFALO, NEW YORK.

DESIGN FOR A CLOCK-CASE.

40,663.

Specification for Design.

Patented Apr. 26, 1910.

Application filed February 5, 1910. Serial No. 542,330. Term of patent 7 years.

To all whom it may concern:

Be it known that I, JESSE M. PEASE, a citizen of the United States, residing at Buffalo, in the county of Erie and State of New York, have invented a new, original, and ornamental Design for Clock-Cases, of which the following is a specification, reference being had to the accompanying drawing, forming a part thereof.

The figure is a perspective view of a clock-case showing my design.

The design consists in the base and a crescent-shaped body mounted on said base and having a clock-dial between its points.

I claim,

The ornamental design for a clock-case, as shown and described.

JESSE M. PEASE.
